UNITED STATES PATENT OFFICE.

EMIL G. JOHANSON, OF CHICAGO, ILLINOIS.

DESIGN FOR A DIFFUSE COLOR-SCREEN FOR AUTOMOBILE-HEADLIGHTS.

54,320.

Specification for Design.

Patented Dec. 23, 1919.

Application filed July 5, 1919. Serial No. 308,904. Term of patent 3½ years.

To all whom it may concern:

Be it known that I, EMIL G. JOHANSON, a subject of the King of Sweden, residing at Chicago, in the county of Cook and State of Illinois have invented a new, original, and ornamental Design for Diffuse Color-Screens for Automobile-Headlights, of which the following is a specification, reference being had to the accompanying drawing, in which—

Figure 1 is an elevation of the design, and Fig. 2 is a vertical section thereof.

I claim:—

The ornamental design for a diffuse color screen for automobile headlights, as shown. In testimony whereof I affix my signature.

EMIL G. JOHANSON.
